WARDROBE SUITCASE

Julius Ritter, Jr., Racine, Wis., assignor to Hartmann Trunk Company, Racine, Wis., a corporation of Wisconsin

Application June 24, 1935, Serial No. 28,106

6 Claims. (Cl. 190—41)

This invention relates in general to improvements in wardrobe suitcases.

A general object of the invention is to provide an improved wardrobe suitcase which is simple, compact, and light in construction, and which is moreover highly efficient and practical in use.

The present tendencies in travel make it desirable for luggage manufacturers to reduce to a minimum the size and weight of luggage cases, without undesirably sacrificing available space. The traveling public also demands that cases for wearing apparel such as suits, coats, and the like be adapted to effectively conceal and confine the garments without undesirably crushing and wringing the same and that the garments be readily accessible without disturbing other articles confined within the carrying case. While it is desirable to have such garments snugly and safely confined within a portion of the case during transportation, it is also frequently desirable to have ready access to any and all of the confined garments so as to be able to remove selected garments without disturbing or mussing any of the others.

It is a more specific object of the present invention to provide an improved wardrobe suitcase which meets all of the above requirements and other special requirements for every class of transportation, and for the traveling trade in general.

There are on the market certain forms of wardrobe suitcases particularly designed for men's suits and coats wherein the garments are foldably confined within one section of the case by means of one or more garment folding frames adapted to engage and fold extended portions of garments draped from a plurality of hangers in superimposed relation within another portion of the case section.

Heretofore, when an attempt has been made to pack several suits or garments in a case of this type, the constructions have been such that while the top or outermost garments were at all times accessible and removable, the same was not true of garments supported inwardly, with the result that an inwardly disposed garment could not be reached and removed without disturbing and disarranging garments outwardly thereof.

It is, therefore, another object of the present invention to overcome the above objection by providing a wardrobe suitcase structure of the class mentioned, wherein inwardly disposed garments may be readily individually removed from their frames and the suitcase without removing, disturbing, or mussing garments outwardly thereof.

A further specific object of the invention is to provide a wardrobe suitcase employing several superimposed hangers which are mounted in such manner that any selected hanger may be removed from the mounting bracket without removing or releasing any of the other hangers.

Another specific object of the invention is the provision of a wardrobe suitcase with hanger mounting means therein for several hangers, arranged so that all of the hangers may be releasably locked in the mounting in a manner so as to permit swinging movement of the hangers, but preventing undesired removal or detachment of any of the hangers relative to the mounting means.

A further specific object of the invention is the provision of a wardrobe suitcase with hanger mounting means therein for several hangers, and constructed so that a hanger can only be removed from the mounting means when it is in a flat position within the case section, removal of a hanger being impossible when it is in a tilted position relative to the case section.

Still another object of the invention is the provision of a wardrobe suitcase having a wardrobe section including folding frame members and hangers, the wardrobe section being removable bodily as a tray for convenience in disposition for loading and unloading operations.

A further object of the invention is to provide a wardrobe suitcase wherein certain classes of garments are entirely foldably confined within a section of the case which is end opening and detachable relative to the other section of the case.

Still another object of the present invention is to provide a wardrobe suitcase wherein a pair of swingable garment folding frames are mounted in one section of the case in a manner so as not to interfere with one another in the independent arrangement of garments thereon.

A further object of the invention is to provide a garment frame equipped wardrobe suitcase wherein special provision is made for the packing of trousers, and the side members of the frames are offset inwardly for this purpose and to permit the folding of portions of the trousers there around.

Another specific object of the invention is to provide a wardrobe suitcase which includes one or more removable garment hangers adapted either for snug confinement within a section of the case, or for effective use when hanging an associated garment in a wardrobe or closet.

These and other specific objects and advan-

tages will be apparent from the following detailed description.

A clear conception of an embodiment of the invention may be had by referring to the drawings accompanying and forming a part of this specification in which like reference characters designate the same or similar parts in the various views:

Fig. 1 is a transverse vertical sectional view 10 through a wardrobe suitcase in closed position;

Fig. 2 is a plan view of the suitcase as opened, a portion of the body section being broken away;

Fig. 3 is a transverse vertical sectional view of the wardrobe section of the suitcase, indicated 15 by line 3—3 of Fig. 2, and with the top or outermost garment folding frame and associated hanger swung to upright positions;

Fig. 4 is a longitudinal vertical sectional view 20 of the wardrobe section with the same frame and hanger in upright position;

Fig. 5 is a plan view of the showings in Figs. 3 and 4 with the outermost garment hanger removed, and illustrating one mode of packing a 25 pair of trousers in addition to other pieces of a suit of clothes;

Fig. 6 is an enlarged, fragmentary detail sectional view taken on line 6—6 of Fig. 2;

Fig. 7 is a similar enlarged fragmentary, detail sectional view illustrating the manner in which 30 the hinges permit complete separation and detachment of the case sections; and

Fig. 8 is an enlarged, fragmentary, detail view 35 showing the hanger carrying bracket and the engagement of a hanger therewith, the hanger being shown in an outwardly moved position.

While the invention has been shown herein as being specifically applied to an end-opening wardrobe suitcase, it will be apparent that some 40 of the novel features are capable of more general application, and that the specific disclosure should not therefore be construed as an intent to limit the scope.

The suitcase specifically illustrated is of rectangular form and includes a body section 10, to 45 an end portion of which a wardrobe or cover section 11 is hingedly connected. The hinge connections, as shown in detail in Figs. 6 and 7, are such that the section 11 may, when opened out flatly with respect to the section 10, be detached and entirely bodily removed. For this purpose 50 an exterior end wall of the body section 10 carries pintles 12 pivotally engaged by the curved ends of hooking plates 13 carried by an exterior end wall of the cover section 11. The case sections 55 swing to open position end-wise with respect to each other, attaining the open position of Figs. 2 and 6. To bodily detach or separate the cover section from the body section it is necessary to then raise the cover section to disengage the 60 hooks 13 from the pintles 12, after which the sections may be entirely separated, as in Fig. 7.

While the elongated end opening, separable hinge case has special obvious advantages, the principles of the improved construction herein- 65 after to be described, may, within the scope of the invention, be embodied in a case which opens in the standard manner with adjacent side walls of the sections connected so that one section opens relative to a side of the other section.

70 In the suitcase illustrated the body section 10 constitutes the main section of the case and the top or front wall thereof carries a handle 14. When the cover section 11 is swung into closed relation with respect to the body section it may 75 be locked by means of latches 15. The body

section 10 is susceptible of holding various classes of garments and traveling paraphernalia and is equipped with flexible straps or stays 16 for maintaining articles in position therewithin.

The wardrobe section 11 of the suitcase is 5 adapted to be loaded with garments such as suits, coats, trousers, and the like, and such garments, save for trousers, extend in folded condition transversely of the case section. There is within the case section 11 a pair of pivotal, garment folding U-frames, designated generally by the numerals 17 and 18 respectively. Each frame includes a pair of side arms 19 and 19' respectively, joined respectively at their outer ends by transverse bars 20 and 20'. The innermost frame 17 has side arms a trifle shorter than the side arms 19' of the outermost frame 18 whereby the pivotal connections 21 and 22 of the pairs of arms, are somewhat staggered. By means of the pivotal connections 21 and 22 the arms of each frame are connected to opposite inner-end wall portions of the case section 11 and such connections are adjacent the lower end of the case, when it is in carrying position, with the result that the bars 20 and 21' are disposed adjacent 25 the top portion of the case when it is in carrying position. It should also be observed that the frames 17 and 18 are disposed in superimposed relation, and that the major portions of the side arms 19 and 19' are offset inwardly from 30 the end walls of the case section to provide clearance between the same and said walls for the reception of folded portions of trousers, as will be hereinafter more fully explained.

Secured to the inner surface of the inner or 35 bottom wall and the section 11, intermediate its ends, is a multiple hanger carrying bracket 25. This bracket includes a lower or inner, curved, offset engaging portion 23 with a reduced approach 24 thereto, and an upper or outer, curved, 40 off-set engaging portion 23' with a reduced approach 24' thereto. A locking lever 26 has its inner end pivotally connected to the inner or lower portion of the bracket 25 and is adapted to be normally swung into and out of restrictive 45 engagement with the approaches 24 and 24'.

A pair of coat hangers 27 and 28 are adapted to 50 coact with the bracket 25. The medial portion of each hanger carries a projecting plate 29 with a rectangular opening 30 therein, there being a reduced entrance 31 to said opening. The end portion of the plate, adjacent the reduced entrance 31, is flanged, as at 32, at right angles to the major portion of the plate. Each hanger also has pivotally connected thereto a hook member 55 33, the hooks being susceptible of being moved from the positions shown to opposite projecting positions, permitting, upon removal of the hangers from the case, their being hung in a closet or wardrobe in the usual manner for 60 clothes supporting purposes.

In engaging the lower or inner hanger 27 with the bracket 25, the hanger is positioned flat with respect to the case section and the locking lever 26 is moved to open position. The reduced entrance portion 31 of the hanger plate 29 engages the approach 24 and the hanger is then moved downwardly until the bracket portion 23 lodges within the opening 30. The outer hanger 28 is engaged with the bracket portion 23' in the same 70 manner. When the locking lever 26 is moved to locking position against a side of the reduced approaches 24 and 24', both hangers will be locked within the bracket against undesired removal and dislodgement. The hangers may, 75

however, be individually swung from flat positions through ninety degree angles, to outwardly projecting positions. It should be noted, however, that when a hanger is swung to an outwardly projecting position, even though the locking lever 26 be in open position, such hanger cannot be disengaged from the bracket. This result is accomplished by the hanger plate flanges 32 which then present surfaces to prevent withdrawal through the reduced entrance to the particular curved off-set engaging portion of the bracket, as shown in connection with the upturned hanger in Figs. 3 and 8. Obviously, when either hanger is turned down, and the locking lever is in open position, such hanger may be removed from its mounting by an operation which is the reverse of that described in connection with its attachment. This arrangement is of considerable advantage because if it is desired to remove the inner hanger and garments thereon from the case, the upper hanger, with the garments and frame, may be swung outwardly, and then the lower hanger is readily removable, without disturbing or mussing garments carried by the other assembly.

Assuming that it is the intention to pack the section 11 of the suitcase with two men's suits, the procedure is as follows: The case is first opened out flatly with the section 11 resting horizontally, open side upwardly. Both of the hangers 27 and 28 are removed from the bracket 25. Also, both of the garment folding frames 17 and 18 are swung outwardly of the case section. One pair of trousers 34 may be laid flatly on the bottom of the section, longitudinally thereof and with the legs of the trousers extending over an end wall of the section. The other pair of trousers 35 is positioned in a reverse manner with its legs extending over the other end wall of said section. The coat and vest of one suit are next hung on the hanger 27 in the usual manner, and this hanger is then engaged with the portion 23 of the bracket 25, in the manner previously described. The coat is smoothed and extends over the wall of the section opposite the bracket 25. Thereafter, the U-frame 27 is pivotally moved into the case section 11 and its transverse bar 20 engages the media portion of the coat, while the side bars 19 engage the extended portions of the trousers 34 and 35. The extended portion of the coat is folded over on the bar 20 into the case section, while the extended portions of the trousers are folded over both side bars 19, in the manner shown in Fig. 5. A coat and vest are foldably confined by the outermost hanger and U-frame in the same way. As described, the trousers are ultimately folded over the side members 19 of the U-frame 17. Due to the fact that the major portions of said side members are off-set inwardly from the end walls of the case section, clearance is provided for the accommodation of these portions of the trousers.

In addition to the mode of packing the trousers just described, one pair may be folded on the inner frame as described, and the other pair may be folded in the same manner on the outer frame. Also, one or more pairs of trousers may simply be positioned in folded condition in the section below the inner frame, and not be folded thereon. However, the former manner of arranging the trousers is believed to be preferable because the trousers are engaged by the frame arms and folded portions held thereby against the end walls, and there is less danger of the trousers slipping out of position and being

wrinkled when the case is handled or positioned upright for carrying. It should also be observed that when the packed case is in the position for carrying, as in Fig. 1 the bars of the U-frames are at the top of the case and the coats drape thereover in a natural manner without danger of becoming dislodged.

After the wardrobe section has been packed as described, the garments may be covered and protected by a flexible curtain 36. This curtain is permanently secured along one edge to a side wall of the section 11, while the other edge thereof carries adjustable fastener elements 37 for releasable engagement with fastener elements 38 carried by the opposite wall of the case section.

The case section 10 is adapted to be packed with other classes of garments and articles. If the case is of the separable section type illustrated, the hinges of the two sections should be connected, and then the sections are closed relative to each other and are secured by the latches 15.

During traveling, when the case is opened, the owner may very readily gain access to the inner suit or garment by merely swinging out the outer frame carrying the outer garment. As previously described, the hanger 28 cooperating with the outer frame cannot then be removed, but if the lever 26 is thrown to open position the inner hanger 27 is readily removable. Hence, removal of or access to an inner garment is readily accomplished without mussing or disturbing other, more outwardly disposed garments.

Obviously, the suitcase may be constructed as a conventional, side opening case. Also, if a case for a greater number of suits is desired, the wardrobe section 11 will then become the deeper of the two sections, and will be proportioned so as to accommodate a desired number of hangers and U-frames. If the wardrobe section is the wider or deeper of the two sections it will carry the handle 14. In addition, if the case is of the separable section type and the wardrobe section is arranged with the carrying handle, closure flap means may be provided for the open face of said section so it may be carried and used independently of its other section.

From the foregoing description it will be apparent that the invention provides simple, compact, and readily accessible means for foldably confining garments within one section of a suitcase. The folding devices are arranged and mounted so that convenient access to all portions of the sections is permitted, and so that all garments are readily individually accessible.

It should be understood that it is not desired to limit the invention to the exact details of construction herein shown and described, for various modifications within the scope of the claims may occur to persons skilled in the art.

What is claimed as the invention is:

1. In combination, a housing, a pair of garment folding frames pivotally mounted therein, a pair of garment hangers coacting with the frames in the support and folding of garments mounted on the hangers, means for swingably mounting the hangers within the housing in separated, superimposed relation, means for permitting the independent removal of either hanger from the mounting means while the other hanger is engaged, and means for simultaneously releasably locking both hangers in the mounting means.

2. In combination, a housing, a bracket

- mounted adjacent one wall of the housing, a pair of garment hangers pivotally and separately and independently releasably carried by the bracket, a pair of garment folding frames pivotally mounted adjacent the same wall of the housing and cooperable with said hangers to separately, foldably confine several garments within said housing, and means for simultaneously releasably locking both hangers in the bracket.
3. In combination, a garment housing, a pair of U-frames pivotally mounted within the housing in superimposed relation, a frame being adapted to have garments folded over its transverse portion and other garments folded over its side portions, a pair of hangers for the support of garments which fold over the transverse portions of said frames, means for individually and independently releasably mounting said hangers within the housing in superimposed, spaced-apart relation and remote from the transverse portions of the frame, and means for simultaneously releasably locking both hangers in the mounting means.
4. In a wardrobe case, a garment folding U-frame including a pair of side arms and a transverse bar connecting the outer ends of said side arms, said transverse bar being adapted to have garments draped thereover, and pivotal connections between the inner ends of said side arms and inner wall portions of the case, the major portions of said side arms being off-set inwardly from said case wall portions to provide spaces for the accommodation of portions of other garments folded over said side arms.
5. In a wardrobe case, a hanger removably mounted within a section of the case, a garment folding U-frame including a pair of side arms and a transverse bar connecting the outer ends

of said side arms, said transverse bar being adapted to have the extended portions of garments folded thereover which are draped from the hanger, and pivotal connections between the inner ends of said side arms and inner wall portions of the case, the major portions of said side arms being off-set inwardly from said case wall portions to provide spaces for the accommodation of portions of other garments folded over said side arms.

6. A wardrobe suitcase, comprising a pair of complementary sections, separable hinge connections between adjacent end walls of said sections permitting complete detachment and bodily removal of one section with respect to the other, a pair of garment folding U-frames mounted within one section of the case in superimposed relation, each frame including a pair of side arms and a transverse bar connecting the outer ends of said side arms, said transverse bars being adapted to have the extended portions of garments folded thereover, pivotal connections between the inner ends of said side arms and inner wall portions of said section of the case, the pivotal connections for the arms of one frame being staggered and off-set with respect to the pivotal connections for the arms of the other frame, the major portions of said side arms being off-set inwardly from said section side wall portions to provide spaces for the accommodation of portions of other garments folded over said side arms, a pair of hangers for the support of garments which fold over said transverse bars of the frames, and means for individually and independently releasably, pivotally mounting said hangers within said case section in superimposed, spaced-apart relation and remote from the transverse portions of the frames.
